(57) **CLAIM**

The ornamental design for footwear, as shown and described.

DESCRIPTION

FIG. 1 is a bottom, left perspective view of footwear showing the new design;

FIG. 2 is a right side view thereof;

FIG. 3 is a left side view thereof;

FIG. 4 is a front elevation view of thereof;

FIG. 5 is a rear elevation view of thereof;

FIG. 6 is a top plan view thereof; and,

FIG. 7 is a bottom plan view thereof.

The portions depicted in broken dashed lines of even length illustrate portions of the footwear that form no part of the claimed design. The broken dashed lines of uneven length illustrate the boundary of the claimed design and form no part of the claimed design.

1 Claim, 7 Drawing Sheets
